UNITED STATES PATENT OFFICE.

DANIEL F. GONWARE, OF CHICAGO, ILLINOIS.

JOURNAL-BOX WEAR-PLATE.

1,082,943.

Specification of Letters Patent. Patented Dec. 30, 1913.

Application filed March 23, 1912. Serial No. 685,742.

To all whom it may concern:

Be it known that I, DANIEL F. GONWARE, a citizen of the United States, residing at Chicago, in the county of Cook and State 5 of Illinois, have invented a new and useful Improvement in Journal-Box Wear-Plates, of which the following is a specification.

My invention relates particularly to wear-plates for the journal-boxes of locomotives 10 and analogous constructions.

My primary object is to provide a wear-plate adapted to be interposed between the journal-box and wheel-hub, the wear-plate being adapted to be removed without dis- 15 memberment.

The invention is particularly applicable where the wheel is located outside the journal-box, as in engines, locomotives, tenders, etc.

20 The invention is illustrated in its preferred embodiment in the accompanying drawings, in which—

Figure 1 represents a horizontal sectional view of a journal-box equipped with a wear-plate in accordance with my invention, the section being taken as indicated at line 1 of 25 Fig. 2, and the view showing also a locomotive wheel and axle brokenly; Fig. 2, a vertical section taken as indicated at line 2 of Fig. 1; Fig. 3, a broken vertical section taken as indicated at line 3 of Fig. 2; Fig. 30 4, an inner face view of my improved wear-plate; Fig. 5, an edge elevational view of the same; and Fig. 6, a plan view of the 35 same.

In the construction illustrated, A represents an engine or locomotive wheel secured to or mounted on the end of an axle A'; B a journal-box; and C my improved wear- 40 plate removably interposed between the wheel-hub 1 and the journal-box.

The journal-box B, sometimes called the driving-box, is fitted with the usual brass 2, which rests upon the axle, and has the 45 usual cellar 3 adapted to contain lubricant. It is common to removably secure the cellar 3 between the downward extensions 4 of the journal-box, by means of cellar-bolts 5.

The general form of my improved wear- 50 plate is shown in Fig. 4. It comprises a flat plate 6 adapted to afford a facing for the outer end of the journal-box. The plate 6 is recessed centrally from its lower edge upwardly, as indicated at 7, the recess terminating in a semi-cylindrical upper wall 8 which conforms to the upper half of the

axle A'. The plate 6 is provided at its lateral edges with inturned flanges 9. That is, the flanges 9 are turned away from the wheel. The flanges 9 embrace the flanges 10 with which the journal-box B is provided at its outer end; and the flanges 9 are equipped on their inner faces with flanges 11 which engage grooves 12 with which the flanges 10 are provided in their vertical edge portions. Thus, it will be seen that the wear-plate is connected to the journal-box by vertical guides, which enable the wear-plate to be removed by a vertical movement. It is preferred to equip 70 the upper end of the plate 6 with an in-turned segmental flange 13, which conforms in curvature to the curved upper surface 14 of the outer cross-flange 15 of the journal-box. 75

As described, the plate 6 has downward extensions 16 which flank the axle A'; and these extensions, together with the flanges 9, may terminate somewhat below the cellar 3 of the journal-box, thus enabling the flanges 9 to be provided at their lower ends with perforations 17 which align with perforations in lugs 18 and 19 with which the cellar 3 and the downward extensions 4 of the journal-box are provided at their lower portions. Thus, the outer cellar-bolt 5, suitably lengthened according to necessity, may be employed to secure the wear-plate against working upwardly in its guides. 85

The wear-plate may be of brass, or other material suitable to withstand the wearing action of the hub, due to thrust of the axle. It will be noted that the outer face 20 of the wear-plate affords a wear-surface which contacts with the vertical inner face of the 95 hub.

By providing for the removal of the wear-plate by a movement of withdrawal in its own plane, preferably by a vertical movement, the wear-plate may be removed without dismemberment of the locomotive or tender, as the case may be. That is, it is unnecessary to drop the axle out of its bearing in order to enable a new wearing-surface to be applied to the outer end of the journal-box. In accordance with my improvement, the wear-plate may be removed at will and replaced by a new wear-plate with great facility; or, the wear-plate may be removed and re-faced and then employed again. 105 110

To those who are familiar with the great loss of time and large expense to which rail-

way companies are now subjected to provide against play between the wheel-hub and journal-box, particularly in locomotive construction where the end thrust of the axle is at times enormous and the wearing therefore large, it will at once be appreciated that my invention is of the utmost practical importance and adapted to effect a very great saving in operating expenses.

10 The foregoing detailed description has been given for clearness of understanding only, and no undue limitation should be understood therefrom, but the appended claims should be construed as broadly as 15 permissible in view of the prior art.

What I regard as new, and desire to secure by Letters Patent, is:

1. A wear-plate for the purpose set forth, comprising a plate having its lower edge recessed centrally to accommodate an axle, said plate provided with lateral flanges equipped on their inner surfaces with guide-tenons adapted to slide in lateral grooves at the outer end-portion of a journal-box.

25 2. The combination with a journal-box

having the lateral vertical surfaces of its outer end portion provided with guide-grooves, and a vertically slidable wear-plate having its lower end recessed to accommodate the axle, said wear-plate having flanges 30 embracing the outer end-portion of the journal-box and equipped on their inner surfaces with guide-tenons engaging said grooves, and a bolt connecting said flanges to the lower portion of the journal-box.

35 3. A wear-plate for the purpose set forth, comprising a plate having its lower edge recessed centrally to accommodate an axle, said plate provided with lateral flanges having their inner surfaces equipped with 40 guide-tenons adapted to engage grooves in the lateral vertical surfaces of the outer end-portion of the journal-box, and a segmental flange at the upper portion of said plate adapted to overlie a portion of the journal-box.

DANIEL F. GONWARE.

In presence of—

R. A. SCHAEFER,
O. C. AVISUS.
